SLUG CASTING MACHINE

Alfred W. F. Guest, Brooklyn, N. Y., assignor to
 Mergenthaler Linotype Company, a corporation
 of New York

Application August 23, 1933, Serial No. 686,356

9 Claims. (Cl. 199—53)

This invention relates to improvements in typographical or slug casting machines wherein molten metal is forced by a pump from a metal pot into a mold and against a composed line of matrices to form a type bar or slug.

In such machines the composed line of matrices is presented momentarily against one face of the mold and the mouthpiece of the metal pot is presented against the other face of the mold after which molten metal is injected by the action of the pump from the metal pot, through the mouthpiece, into the mold, and against the line of matrices to form the type bar or slug. The composed line, when thus presented against the face of the mold, is confined endwise between a pair of vise jaws, and prior to the operation of the pump it is justified or expanded to a desired length during which operation the right hand vise jaw is moved outwardly to a predetermined position against a stop and the line is rendered fluid tight to prevent the escape of molten metal therethrough during the casting operation, and to insure that molten metal does not escape through the line during the casting operation it is customary to provide the pump of such machines with a locking mechanism which is automatically released to permit the operation of the pump when the right hand vise jaw is moved outwardly to its predetermined position against the stop and the line is rendered fluid tight. While this arrangement is satisfactory to prevent the escape of molten metal through the line, it frequently happens that the face of the mold is not tight against the line during the casting operation and as a result molten metal escapes therebetween.

Accordingly, an object of the present invention is to provide means to prevent the escape of molten metal between the face of the mold and the line, as well as to prevent the escape of molten metal through the line during the slug casting operation, and to this end the machine is provided with a locking mechanism which prevents the operation of the pump and which is automatically released only when the line between the confining vise jaws is tight and the face of the mold is tight against the line. The locking mechanism desirably employed, in the present embodiment of the invention, is the same as is commonly used in machines of this sort and comprises a fore-and-aft main lever which is pivotally mounted intermediate its ends on the main frame of the machine. The movement of the lever to free the pump, however, instead of being dependent solely upon the movement of the right-hand vise jaw outwardly against its fixed stop is also dependent upon the forward movement of the mold into engagement with the composed line.

For a clearer understanding of this invention reference may be had to the accompanying drawings, in which the invention is shown as applied

to a typographical machine of the sort generally shown and described in U. S. Letters Patent No. 436,532, granted to O. Mergenthaler on September 16, 1890 but it is to be understood that the invention is equally applicable to other types of line casting machines. In the drawings the invention is shown merely in preferred form and by way of example but obviously many changes and variations may be made therein and in its mode of application which will be still comprised within its spirit. It should, therefore, be understood that the invention is not limited to any specific form or embodiment except in so far as such limitations are specified in the claims.

Referring to the drawings:

Figure 1 is a front elevational view with portions broken away of a typographical machine embodying the principles of the present invention.

Figure 2 is a top plan view.

Figure 3 is an enlarged top plan view showing the lever mechanism prior to the line justification operation.

Figure 4 is an enlarged front elevational view of the lever releasing mechanism prior to the line justification operation.

Figure 5 is a top view, in section, showing the mold brought forward into engagement with the line.

Fig. 6 is an enlarged front elevational view, partially in section, of the lever releasing mechanism after the line has been justified and the mold brought forward into engagement with the line.

As shown, the composed line comprises a plurality of character bearing matrices 10 and interposed spacebands 11 confined endwise in front of a mold 12 between a left-hand vise jaw 13 and an oppositely disposed right-hand vise jaw 14. As is usual in machines of this type the vise jaws 13 and 14 are slidably mounted in a vise frame 15. Prior to the line casting operation the line thus confined between the vise jaws 13 and 14 is justified or elongated to a predetermined length by elevating the line justification bar 16 against the lower ends of the spacebands 11, thereby expanding the spacebands 11 which serve to force the vise jaws outwardly to predetermined positions, the left-hand vise jaw 13 being forced against an adjustable stop 13a carried by the vise frame 15 and the right-hand vise jaw 14 being forced against a fixed stop 14a which is also carried by the vise frame 15. As the spacebands are expanded and the vise jaws move outwardly against the stops the matrices and spacebands are forced tightly and firmly against one another and the end matrices are forced tightly and firmly against the inner faces of the vise jaws thus providing fluid tight joints therebetween.

The mold 12 employed in machines of this class has a slot or cavity 17 therein for the casting of

the type line or slug and it is mounted on a mold wheel 18 which carries it forwardly against the rear face of the line prior to the line casting operation and away from the rear face of the line after the type line or slug has been cast.

The casting mechanism employed in machines of this class comprises the usual metal pot 19 wherein molten type metal is stored and in the lower end of which a well (not shown) is positioned. A plunger is positioned in the well and it is adapted to be reciprocated therein during the casting operation by means of a plunger rod 20 which is connected at its upper end to an actuating rod 21. As usual the metal pot is mounted to rock or tilt forwardly into casting position against the rear face of the mold 12 prior to the line casting operation and rearwardly away from the mold after the casting operation has been completed, and while the metal pot is so positioned against the rear face of the mold the plunger operates to force molten metal into the mold and against the line of matrices to form a type line or slug. Such movement of the mold and the metal pot to and from casting position and the manner of injecting the molten type metal from the metal pot into the mold and against the line to produce a type line or slug is the same as commonly take place in typographical machines of the class referred to and further explanation thereof is deemed unnecessary except to state that it is customary to provide such machines with a locking mechanism which prevents the reciprocation of the plunger until the line between the vise jaws is fluid tight.

The locking device, as usual, comprises a main lever 23 pivotally mounted intermediate its ends on a pivot pin 24 which extends upwardly from the main frame of the machine. The rear end of the main lever terminates in a yoke 25 which engages the forward end 26 of a secondary lever 27. The secondary lever 27 is likewise pivotally mounted intermediate its end on a pivot pin 28 which also extends upwardly from the main frame of the machine. The rear end of the secondary lever is maintained, by means of a spring 31, beneath a stop shoulder 30 which is carried by the actuating rod 21. The front end of the main lever 23 extends forwardly beyond the front of the vise jaw 14 and that portion of the lever adjacent the end of the vise jaw is provided with an adjustable screw 32. An outward movement of the forward end of the main lever produces an inward movement of the rear end of the yoke 25 and an inward movement of the yoke causes an inward movement of the front end and an outward movement of the rear end of the secondary lever 27. Consequently, when the front end of the main lever 23 is moved outwardly a sufficient distance the rear end of the secondary lever 27 is forced outwardly, against the action of the spring 31, from beneath the stop shoulder 30, thus permitting the reciprocation of the plunger. It will be observed that the forward ends of the levers are short as compared with the rear ends, the result being that a comparatively short movement of the outer end of the main lever 23 is sufficient to release the plunger.

In accordance with the present invention the release of the locking mechanism is effected only when the line between the vise jaws 13 and 14 is fluid tight and the face of the mold 12 is pressed tightly against the line of matrices, and to this end the right-hand vise jaw 14 is provided with movable co-acting plunger rods 33 and 34. The plunger rod 33 is slidably mounted in an opening

which extends through the jaw 14 in front of the mold 12 and in the direction of travel of the mold as the mold is moved forward into casting position. The plunger rod 34 is slidably mounted in a cavity which extends upwardly and outwardly through the central portion of the jaw from the opening in which the plunger rod 33 is positioned and which opens from the right end face of the jaw opposite the head of the adjusting screw 32. It is thus seen that the plunger rod 34 is disposed in the jaw 14 in a plane at right angles to the rod 33. The upper end of the plunger rod 34 is beveled so as to conform with the end face of the vise jaw and it is normally maintained flush therewith by a leaf spring 35. The lower end of the plunger rod 34 is also beveled and engages a beveled face at the outer end of the plunger rod 33. The inner end of the plunger rod 33 extends a slight distance beyond the inner face of the jaw 14 and it is engaged by the mold 12 as the mold moves forward into casting position. To reduce the friction between the beveled faces of the co-acting plunger rods, a groove 36 is cut in the plunger rod 33 at the outer end of the tapered face thereon, and to prevent displacement of the engaging beveled faces the groove is cut a slight distance back of the outer end so as to provide a retaining wall 37. As the mold 12 moves forward into casting position against the rear face of the line it engages the inner end of the plunger rod 33 and thus forces the rod outwardly in the direction of travel of the mold. As the plunger rod 33 is thus forced outwardly, the co-acting plunger rod 34, due to the sliding contact between the beveled faces, is forced upwardly and outwardly in a plane at right angles thereto against the action of the spring 35 towards the head of the screw 32. Under such conditions, it is seen that the plunger rod 34 is carried to the right by two separate movements prior to the normal line casting operation, one movement being produced as the jaw 14, in which the co-acting plunger rods are positioned, is forced to the right to a predetermined position against the fixed stop 14a during line justification and the other movement being produced as the mold 12 is moved forward into line casting position. The position of the screw 32 is adjusted in the outer end of the main lever 23 so that it is moved to the right sufficient to release the plunger only when the plunger rod 34 has been moved to the right to its extreme position by both movements. Consequently, when the jaw 14 is in its predetermined position against the fixed stop 14a and the front face of the mold is advanced tight against the rear face of the line the plunger rod 34 is forced outwardly, thereby forcing the spring 35 against the head of the screw 32 and thus forcing the end of the main lever 23 outwardly sufficient to release the locking mechanism and permit the reciprocation of the plunger. In the event, however, that the spacebands do not act properly or that there are an insufficient number of matrices and spacebands between the confining jaws so that the elements which make up the line are not forced tight against one another and the jaw 14 is not moved to its predetermined position during line justification, or in the event that the outer face of the mold 12 is not moved tight against the rear face of the line so as to force the plunger rod 34 outwardly to its extreme position, the end of the screw 32 is either not engaged at all or else it is not moved outwardly sufficient to disengage the inner end of the secondary lever 27 from be- 75

neath the shoulder 30 and as a result the plunger remains locked and reciprocation thereof is prevented.

Having thus described my invention, I claim:

5   1. In a slug casting machine having a pair
of vise jaws for holding a composed line of mat-
rices, a mold, means for advancing said mold
into engagement with said line, a metal pot con-
taining molten type metal, a reciprocable plunger
positioned in said pot and adapted to force mol-
ten metal therefrom into said mold and against
10   said line to form a slug, means for preventing
the reciprocation of said plunger, and means car-
ried by one of said jaws and operated by said
mold as it advances into engagement with said
line to render said plunger reciprocating pre-
15   venting means inoperative when said jaw is in a
predetermined position.

2. In a slug casting machine having a pair of vise jaws for holding a composed line of matrices, a mold, means for advancing said mold into engagement with said line, a metal pot containing molten type metal, a reciprocable plunger positioned in said pot and adapted to force molten metal therefrom into said mold and against said line to form a slug, means operative to prevent the reciprocation of said plunger, and co-acting plunger rods carried by one of said jaws and operated by said mold as it advances into engagement with said line to render said plunger reciprocation preventing means inoperative when said jaw is in a predetermined position.

3. In a slug casting machine having a pair of vise jaws for holding a composed line of matrices, a mold, means for advancing said mold into engagement with said line, a metal pot containing molten type metal, a reciprocable plunger positioned in said pot and adapted to force molten metal therefrom into said mold and against 35 said line to form a slug, a locking device operative to prevent the reciprocation of said plunger, and means carried by one of said jaws and responsive to the advancement of said mold into engagement with said line to release said locking 40 device when said jaw is in a predetermined position.

tion.

4. In a slug casting machine having a pair of vise jaws for holding a composed line of matrices, a mold, means for advancing said mold into engagement with said line, a metal pot containing molten type metal, a reciprocable plunger positioned in said pot, and adapted to force molten metal therefrom into said mold and against said line to form a slug, a locking device operative 50 to prevent the reciprocation of said plunger, and co-acting plunger rods carried by one of said jaws and operated by said mold as it advances 55 into engagement with said line to release said locking device when said jaw is in a predetermined position.

60   5. In a slug casting machine having a pair of vise jaws for holding a composed line of matrices, means for rendering said line tight during which one of said jaws is moved to a predetermined position, a mold, means for advancing said mold 65 into engagement with said line, a metal pot containing molten type metal, a reciprocable plunger positioned in said pot and adapted to force molten metal therefrom into said mold and against said line to form a slug, a locking device 70 operative to prevent the reciprocation of said plunger, and means carried by said displaced jaw and actuated by the advancement of said mold.

to release said locking device to permit the reciprocation of said plunger when said displaced jaw is in said predetermined position.

6. In a slug casting machine having a pair of vise jaws for holding a composed line of matrices, means for rendering said line tight during which one of said jaws is moved to a predetermined position, a mold, means for advancing said mold into engagement with said line, a metal pot containing molten type metal, a reciprocable plunger positioned in said pot and adapted to force molten metal therefrom into said mold and against said line to form a slug, a locking device operative to prevent the reciprocation of said plunger, and co-acting means carried by said displaced jaw and actuated by the advancement of said mold to release said locking device when said displaced jaw is in said predetermined position. 5 10 15

7. In a slug casting machine having a pair of vise jaws for holding a composed line of matrices, means for rendering said line tight during which one of said jaws is moved to a predetermined position, a mold, means for advancing said mold into engagement with said line, a metal pot containing molten type metal, a reciprocable plunger positioned in said pot and adapted to force molten metal therefrom into said mold and against said line to form a slug, a locking device operative to prevent the reciprocation of said plunger, and co-acting plunger rods carried by said displaced jaw and actuated by the advancement of said mold to release said locking mechanism when said displaced jaw is in said predetermined position. 20 25 30 35

8. In a slug casting machine having a pair of vise jaws for holding a composed line of matrices, means for justifying said line during which one of said jaws is moved to a predetermined position, a mold, means for advancing said mold 40 into engagement with said line, a metal pot containing molten type metal, a reciprocable plunger positioned in said pot and adapted to force molten metal therefrom into said mold and against said line to form a slug, a locking mechanism operative to prevent the reciprocation of said plunger, movable members carried by said displaced jaw and actuated by said mold as said mold is moved into engagement with said line, and means responsive to the actuation of said members and the movement of said jaw during line justification to release said locking mechanism to permit the reciprocation of said plunger. 45 50

9. In a slug casting machine having a pair of vise jaws for holding a composed line of matrices, 55 means for justifying said line during which one of said jaws is moved to a predetermined position, a mold, means for advancing said mold into engagement with said line, co-acting plunger rods carried by said displaced jaw and actuated by the advancement of said mold, a metal pot containing molten metal, a reciprocable plunger positioned in said pot and adapted to force molten metal therefrom into said mold and against said line to form a slug, a locking device 60 operative to prevent the reciprocation of said plunger, and means responsive to the movement of said jaw during line justification and the actuation of said co-acting plunger rods for releasing said locking device to permit the reciprocation of 65 said plunger. 70

ALFRED W. F. GUEST.
